United States Patent Office

Des. 203,833
Patented Feb. 22, 1966

203,833

MAGNETIC TAPE TRANSPORT UNIT

Francis A. Farey, Northfield, Ill., assignor to Ampex Corporation, Redwood City, Calif., a corporation of California

Filed May 8, 1964, Ser. No. 79,882

Term of patent 14 years

(Cl. D26—14)

Des. 203,833

PAGE 2

FIGURE 1 is a front and right side perspective view of a magnetic tape transport unit with the cover mounted, showing my new design;

FIGURE 2 is a rear and left side perspective view of the transport of FIGURE 1 with the cover removed; and

FIGURE 3 is a front and right side perspective view of the transport with the cover removed.

I claim:

The ornamental design for a magnetic tape transport unit, substantially as shown.
